UNITED STATES PATENT OFFICE.

ANTHONY P. SMITH, OF BROOKLYN, NEW YORK.

ADJUSTABLE FLY-SCREEN AND SHADE.

1,042,491.

Specification of Letters Patent.

Patented Oct. 29, 1912.

Application filed January 27, 1912. Serial No. 673,763.

To all whom it may concern:

Be it known that I, ANTHONY P. SMITH, a citizen of the United States, residing at Brooklyn, in the county of Kings and State 5 of New York, have invented certain new and useful Improvements in Adjustable Fly-Screens and Shades, of which the following is a specification, reference being had to the accompanying drawings.

10 This invention comprehends certain new and useful improvements in screens and shades, and the invention has for its primary object an improved construction of a fly screen and shade which may be easily 15 mounted in a window frame, the screen being extended automatically as the window is raised and automatically rolled up as the window is lowered, whereby the space between the lower edge of the window and the 20 window sill will be at all times properly shaded and protected from the entrance of flies, mosquitoes or similar insects.

The invention has for a further object a screen and shade of this character which is 25 laterally adjustable so that it may fit windows of different widths, the parts being so constructed and arranged that they can be cheaply manufactured and readily assembled and easily adjusted. And the invention 30 further aims to generally improve this class of devices and to render them more useful and commercially desirable.

With these and other objects in view as will more fully appear as the description 35 proceeds, the invention consists in certain constructions, arrangements and combinations of parts that I shall hereinafter more fully describe and claim.

For a full understanding of the invention, 40 reference is to be had to the following description and accompanying drawings, in which—

Figure 1 is a face view of a portion of a window equipped with my improved fly 45 screen and shade. Fig. 2 is a transverse sectional view through the automatically winding roller of the device. Figs. 3 and 4 are views of the roller gudgeons to which the winding spring is attached at its ends. 50 Fig. 5 is a detail perspective view of the casing which is designed to receive the roller and the wound up portion of the shade and screen so as to protect the working parts. Fig. 6 is a longitudinal sectional 55 view of the roller and a portion of the casing or receiver therefor, parts being shown broken away and other parts in side eleva-

tion. Fig. 7 is a detail view of the holding device for the relatively free end of the screen or shade. Fig. 8 is an enlarged fragmentary sectional view thereof. Fig. 9 is a transverse sectional view on line 9—9 of Fig. 7. Fig. 10 is a detail perspective view of one of the gudgeon holding plates, and Fig. 11 is a transverse sectional view on line 11—11 of Fig. 7.

Corresponding and like parts are referred to in the following description and designated in the accompanying drawings by like reference characters.

In carrying out my invention, a casing 1 is mounted in the window frame, being secured to the lower end thereof by brackets 42 or the like, said casing being constructed of telescopic substantially cylindrical sections split at one side to form a slot 2 extending transversely of the window frame. The edges in the split portion of the outermost section of this telescopic tubular casing 1 are turned inwardly as best illustrated 80 in Fig. 5 and as indicated at 40 to engage the corresponding edges of the other section, whereby the two sections will be at all times, held in proper relation to each other as regards the slot 2, so that they may be 85 easily adjusted before being secured permanently in place. Mounted within the casing 1 is a spring roller which is constructed in sections designated 3 and 4, respectively, telescopically mounted in relation to each other. The section 4 is tubular 90 as best illustrated in Fig. 6 and receives the reduced tubular stem 5 of the section 3, the stem 5 being formed with a longitudinal rib 25 which works within a corresponding 95 groove formed in the section 4, so that the two parts or sections of the roller will be at all times, held from turning one relative to the other. The roller spring 14 is mounted within these two sections 3 and 4 and extends entirely therethrough as shown, the 100 ends of said spring being respectively connected to gudgeons designated 43 and 41, said gudgeons being mounted in the usual manner to shade roller gudgeons in plates 105 secured to the window frame, one of said plates being designated 44 and shown in detail in Fig. 10.

The holding device 47 embodies a bar 48 which is formed at each end with a longitudinal bore or recess 49, expansion springs 50 being mounted in said recesses and pressing outwardly upon stems 51 that are provided at their outer ends with blocks 52

adapted to fit in the sash receiving grooves of the window frame, whereby the holding device will adapt itself to window frames of different widths. The bar 48 is formed 5 with two longitudinally extending grooves 6 and in these grooves wires 45 are connected at their ends by studs 46 or similar fastening devices. Each section or strip of the fly screen and shade proper (21 and 22) is 10 looped around one end of the bar 48 and is formed at its inner side with a hem by which it is adjustably mounted upon one of the wires or cords 45. It will thus be understood that the outer side edges of the strips 15 21 and 22 may be caused to snugly fit the sides of the window frame throughout their length and to be adjusted laterally, either inward or outward, according as the roller is extended or contracted in length. In order 20 to detachably connect the holding device to the window, I have shown in the present instance, a tab 7 which is formed with a slot by which it is adapted to engage a stud 8 or the like secured to the bottom of the 25 window, as best illustrated in Fig. 1.

It is to be understood that those parts of applicant's device which are directly secured to the window sash by the tab 7 and stud 8, extend transversely underneath the sash and 30 consequently if there were not parts like the blocks 52 or similar devices mounted in the grooves of the window-frame, the screen-holding device would have a tendency to skew around. The blocks 52 prevent this.

35 From the foregoing description in connection with the accompanying drawings, the operation of my improved automatically extensible and contractible fly screen and shade will be apparent. When the casing 1 and the roller are installed in the window frame and the strips or sections 21 and 22 are extended laterally to the required extent, the tab 7 is secured to the stud 8, and thereafter, in the raising and lowering of the 40 window, the fly screen and shade will be automatically extended or withdrawn into the casing 1. Thus the space between the lower edge of the window and the window sill will at all times, be properly screened 45 and protected from ingress of flies, mosquitoes or other insects, while at the same time, when the window is lowered, the screen will be entirely out of the way and will not have to be removed as is the case 50 with the ordinary screens heretofore employed.

While the accompanying drawings illustrate what I believe to be the preferred embodiment of my invention, it is to be understood that the invention is not limited thereto, but that various changes may be made 60 in the construction, arrangement and proportions of the parts without departing from

the scope of the invention as defined in the 65 appended claims.

Having thus described my invention, I claim:

1. A device of the character described, including a roller, a screen mounted thereon and constructed in separate strips adapted 70 to overlap at their inner edges, a bar arranged for attachment to a window, and longitudinally extending wires secured to said bar, the ends of the strips at their inner edges being lapped upon said wires 75 for the purpose specified.

2. A device of the class described, including a telescopic casing adapted to be secured to a window frame, an extensible roller mounted in said casing, a shade and 80 screen secured to said roller and constructed in separate strips, and means for connecting one edge of said screen to a window, said means embodying a bar, wires secured to said bar and extending longitudinally 85 thereof, the strips being movably connected to said wires, and a device carried by said bar for detachable connection to said window.

3. A device of the character described, including a roller, a screen mounted thereon and constructed in separate strips adapted 90 to overlap at their inner edges, a bar arranged for attachment to a window, and longitudinally extending wires secured to 95 said bar, the ends of the strips at their inner edges being looped upon said wires and at their outer edges encircling said bar.

4. A device of the character described, including a roller, a screen constructed in separate strips secured to one end of said roller, a bar arranged for attachment to a window and formed with longitudinal grooves, and wires connected to said bar and extending along the grooves, the strips 100 at one end being looped at their outer edges over the bar and being looped at their inner edges over the wires, as and for the purposes set forth.

5. A device of the character described, including a roller, a laterally extensible screen mounted thereon, and a bar to which one end of the screen is connected, the bar being arranged for attachment to a window and formed at each end with a longitudinal 115 opening, expansion springs mounted in said openings, and stems mounted in said openings and engaging said springs, the stems being provided at their outer ends with blocks for the purposes specified.

In testimony whereof I hereunto affix my signature in the presence of two witnesses.

ANTHONY P. SMITH.
